UNITED STATES PATENT OFFICE

JOHN S. PHELPS, OF WHITTIER, CALIFORNIA

ROLLER TYPE STAMPING MACHINE

Application filed December 8, 1930. Serial No. 500,926.

My invention relates to means for stamping moving articles, and relates particularly to a stamping device for use on a conveyor to stamp articles or objects, such as boxes or 5 containers, as they move along the conveyor.

My invention is of especial utility in placing identification marks, such as serial numbers, classifications, or emblems, on packages or containers after they are packed with commodities, these marks imparting to an observer desired information regarding the contents of the packages or containers. As an example of the use of my invention, the fruit packing industry may be cited. Herein the 10 fruits are graded and selected, and different grades and selected fruits are packed in boxes or other containers which are marked in a manner to indicate the grade or size of the fruit therein. My invention may be attached to a conveyor which is associated with a packing machine or cover nailing machine for a fruit box so that each box as it passes along the conveyor will be stamped with the 15 identification or designating marks.

It is an object of my invention to provide an automatic stamping device for stamping articles as they travel along a conveyor, having a roller stamping member which stamps the articles as they roll along the face there- 20 of.

It is an object of the invention to provide a device of this character having means for supporting and controlling the stamping roller in such a manner that the stamping roller will stamp the ends of the articles as 25 they travel along the conveyor.

A further object of the invention is to provide a stamping device of this character having a supporting means for the stamping roller which will hold the stamping roller in position to engage the end of an approaching article and will produce a translational movement of the roller in lateral direction as the roller is moved forwardly by the moving article, thereby accomplishing a rolling action of the stamping roller in lateral direction along the end of the article.

It is a further object of the invention to provide a roller type box stamping machine 30 having a printing roller adapted to roll in

engagement with a face of an article, and having means for removing the printing roller from engagement with the face of the article after the printing roller has moved through a prescribed distance.

A further object of the invention is to provide means for preventing reverse rotation of the printing roller after it is lifted from engagement with the face of the box.

Another object of the invention is to provide means for continuing the rotation of the printing roller after it has been removed from engagement with the face of the article, thereby assuring complete inking of the printing member carried on the printing roller.

The invention comprehends a device having a roller adapted to be applied to a face of an article as it moves along a conveyor. Although the printing roller may be placed so as to operate against any selected face of the article, the preferred forms of the invention show it equipped with parts whereby it will move along the ends of the article. This construction is adopted for the reason that as a general practice the labels of fruit boxes are placed on the ends of the boxes, and as I am herein showing the preferred forms of my invention adapted for use in the fruit packing industry, I have accordingly embodied the invention in a form suitable for placing marks on the ends of the boxes.

Further objects and advantages of the invention will be made evident throughout the following part of the specification.

Referring to the drawings, which are for illustrative purposes only,

Fig. 1 is a plan view showing a preferred and simple embodiment of my invention in the position which it assumes when it is first engaged by the box or article which travels along the conveyor.

Fig. 2 is a plan view showing the stamping device with the stamping roller removed from engagement with the front end of the box.

Fig. 3 is a plan view showing the stamping device with its parts in the position which they occupy just before disengagement with the box which has been stamped.

Fig. 4 is a partly sectioned elevational view taken on a plane represented by the line 4—4 of Fig. 1.

Fig. 5 is an enlarged section on a plane 5 represented by the line 5—5 of Fig. 2.

Fig. 6 is a view showing an alternative form of my invention in which the stamping roller is adapted to stamp the rear end of a box. In this view the parts are shown with the 10 stamping roller held in disengagement with the box.

Fig. 7 is a plan view similar to Fig. 6 but showing the alternative form of stamping device with the parts thereof in a position occupied when the stamping roller is in engagement with the rear end of the box.

A conveyor 10 with which my invention may be practiced may have side bars 11 and 12 supported by legs 13 and in turn supporting rollers 14 over which a traveling member, such as a belt 15, moves. In the form of the invention shown in Figs. 1 to 5 inclusive I provide a rotary printing or stamping member in the form of a printing roller 16 20 having printing elements 17, such as letters, numbers, or characters, and being adapted to rotate on a shaft 18 which lies in a plane parallel to the front end 20 of an article or box 21 which is to be stamped as it moves forwardly or rightwardly along the conveyor 10 as indicated by an arrow 22 of Fig. 1. The shaft 18 forms a part of a supporting means 23 for the printing roller and is non-rotatable on its own axis. As shown in Fig. 35, the printing roller 16 is of hollow construction and has a spring 24 therein, one end of which is secured at 25 to the shaft 18 and the other end of which is secured at 26 to the printing roller 16. This spring 24 exerts a 40 resilient force on the printing roller 16 which tends to rotate it in anti-clockwise direction as indicated by the arrow 27 of Fig. 1. The supporting means 23 comprises an arm 28 hinged on a vertical pin 30 carried between 45 the upper and lower horizontal plates 31 and 32 of a supporting bracket 33. As shown in Fig. 4, a spring 34 is provided for normally rotating the supporting means 23 in anti-clockwise direction as indicated by the arrow 35 of Fig. 1. For inking the printing elements 17 I provide inking rollers 36 and 37 which are held resiliently in operative positions by pairs of springs 38 and 40. The invention also provides means 41 for lifting 50 the printing roller 16 from engagement with the end 20 of the box 21 when the roller has rolled across the face 20 through a sufficient distance to complete an impression of the printing elements 17. This means 41 includes a roller member 42 supported on an arm 43 in position for engagement with the end 20 of the box 21. The arm 43 has a rearwardly extending portion 44 of U-shaped 60 form and including upper and lower legs 45 and 46 connected together by a vertical bar

47, as shown in Fig. 4. The arm 43 is hinged on upper and lower bolts 48 which are carried by the plates 31 and 32 of the bracket 33 and are positioned somewhat forwardly or to the right of the pivot 30 which carries the supporting means 23. By means of a bracket 50 mounted on the vertical bar 47 of the retracting means 41, a roller 51 is carried in position for engaging an adjustable member 52 consisting of a plate hinged at 53 to the rearward end 54 of the lever 28, the spacing between the rearward end 54 and the plate 52 being controlled by an adjustment screw 55.

The operation of the device is substantially as follows: When not engaged by an article, such as the box 21, or at the time of initial engagement, the parts of the device are disposed as shown in Fig. 1. It will be perceived that the printing elements 17 carried on the printing roller 16 are to the left of the point at which the printing roller 16 engages the front end 20 of the box 21. The spring 24 shown in Fig. 5 normally holds the printing roller in this position which is determined by stops consisting of projections 56 and 57 mounted respectively on the roller 16 and the upper plate 58 of a pair of plates 58 and 59 which constitute the forward end of the supporting means 23. As the box 21 continues to move rightwardly or forwardly, as indicated by the arrow 22 of Fig. 1, the supporting means 23 is caused to rotate in clockwise direction on the pivot member 30 with the result that the printing roller 16 will swing through an arc 61 and with the result that as such printing roller 16 moves through the arc 61 it will roll in clockwise direction across the front end 20 of the box 21. During this forward movement of the box 21, the front end 20 thereof approaches the roller 42 of the retracting means 41 and swings the retracting means 41 in clockwise direction around the bolts 48, causing the roller 51 to exert a leftward force against the adjustable member 52 on the rearward end 54 of the arm 28 so as to cause the supporting means 23 to move faster than the speed at which it would be moved by the box 21, with the result of lifting the printing roller from engagement with the front end 20 of the box 21. This lifting action is accomplished as a result of the placing and proportioning of the retracting means 41. It will be noted that the front end 63 of the arm 43 is shorter than the rear end 44 thereof so that the movement of the roller 51 is greater than the movement of the roller 42 and is also greater than the movement of the printing roller 16. As a result of such proportioning and disposal of parts, the printing roller 16 is lifted from engagement with the front 20 of the box 21 before the roller 16 has reached the corner 64 of the box 21.

In Fig. 2 I show the parts of the stamping device after the roller 42 has passed the cor- 130

ner 64 and is traveling down the side 62 of the box. It will be noted that the supporting means 23 is in a position to hold the printing roller 16 a considerable distance from the box 21. To prevent anti-clockwise rotation of the printing roller 16 as it is lifted from engagement with the front 20 of the box 21, and also to continue the clockwise rotation thereof so as to carry the printing elements 10 across the inking roller 36, I provide an automatic means for rotating the roller 16 in clockwise direction after it has disengaged the box 21. This automatic means consists of a lever 65 which is hinged to the arm 28 15 by means of brackets 66 which engage a vertical pin 67, which pin 67 in turn engages brackets 68 projecting from the arm 28. By means of studs 70 which project downwardly from the upper plate 31, rollers 71 and 72 20 are supported in position to consecutively engage the rearward end 74 of the arm 65 as the supporting means 23 swings from its position of Fig. 1 to its position of Fig. 2. This consecutive engagement of the rearward end 74 25 of the arm 65 with the rollers 71 and 72 causes the arm 65 to swing in clockwise direction from its position of Fig. 1 to the position in which it is shown in Fig. 2 and to pull outwardly on a flexible strap or band 75 which 30 is connected at 76 to the front end of the arm 65 and is also wound on the roller 16, causing the band 75 to be unwound from the roller 16 and the roller 16 to be rotated in clockwise direction whereby to carry the printing elements 17 across the inking roller 36.

As the box 21 continues to move along the roller 42, as shown in Fig. 2, the roller 42 approaches the rearward corner 77 of the box 21, and upon leaving the corner 77 it 40 will swing in anti-clockwise direction into the space following the rear end 78 of the box 21, as shown in Fig. 3. This inward or anti-clockwise movement of the member 42 permits the supporting means 23 to rotate in anti-clockwise direction through such distance that a guard 80 formed on the forward end of the member 23 will engage the side 62 adjacent the rearward corner 77, thus preventing the printing roller 16 from swinging 45 inwardly into engagement with the corner 77 as the roller 42 disengages the corner 77. As the box 21 moves further in rightward direction from the position in which it is shown in Fig. 3, the guard 80 will drop off 50 or disengage the corner 77, and all of the parts of the printing mechanism will swing into the position in which they are shown in Fig. 1 preparatory to operative engagement with a consecutive box on the conveyor 10.

In the form of my invention shown in Figs. 1 to 5 inclusive I have shown a device for printing the forward end of a box. For convenience, the parts supporting the printing roller and the roller 42 are mounted to

the side of the conveyor so that the parts may swing out of the path of the box 21 as it travels along the conveyor. The arms 28 and 43 in this embodiment of the invention are swung through horizontal planes, but it will be recognized that these arms may be positioned so as to swing through vertical planes by placing the pivot members 30 and 48 either above or below the conveyor.

In Fig. 6 I show my invention adapted to print the rearward end of a box 82 which is traveling in leftward direction, as indicated by an arrow 83, along a conveyor which may be also identified by the numeral 10. To the parts shown in Figs. 1 to 5 I have merely added a retracting means 84 which consists of an arm 85 pivoted at 86 to a bracket 87 and having an adjustable extension or end 88 secured thereto by bolts 89, and an adjustable link 91 which is pivotally connected to the arm 85 at 92 and is also pivotally connected to the rearward portion 44 of the arm 43 by means of a bracket 93. During the period of disengagement with the box 82, and at the time of disengagement therewith, the parts are in the positions shown in Fig. 7. It will be noted that the arm 85 projects inwardly across the path of travel of the box 82 so that the extension 88 will be engaged as the box 82 traveling in leftward direction reaches the plane of the parts 85 and 86. After the box 82 engages the extension 88, its further leftward movement will cause the extension 88 to swing leftwardly into the position shown in Fig. 6, 100 swinging the arm 85 into a similar position, and through the link 91 causing the arm 43 to swing from the position of Fig. 7 to the position of Fig. 6, this movement of the arm 43 causing the printing roller supporting means 23 to be withdrawn into fully retracted position, during which movement of the supporting means 23 the arm 65 will be rotated in clockwise direction and the band or strap 75 will be thereby unwound, causing 105 rotation of the printing roller 16 across the inking roller 36. When the rightward corner 95 of the box 82 passes the end 96 of the extension 88, the arm 85 is left free to swing in clockwise direction. The roller 42 then 110 drops into engagement with the side 97 of the box 82, permitting the supporting means 23 to swing inwardly through a short distance. When the corner 95 is reached, the roller 42 will roll around this corner 95 onto 115 the rear end 98 of the box 82, and as it traverses the rear end 98 of the box 82, the roller 42 will permit the arm 43 to swing in anti-clockwise direction so as to permit the supporting means 23 to swing in anti-clockwise direction and bring the printing roller 16 into engagement with the rear end 98, after which the printing roller 16 will roll in anti-clockwise direction across the end 98 of the box 82 toward the position in which 120 125

it is shown in Fig. 7, at which time the continued leftward or forward travel of the box 82 will move the box from engagement with the printing roller, leaving the printing roller 16 in an inactive position corresponding to the position of the retracting means 84 in readiness for the approach and printing of a consecutive box in the manner above described. It will be noted that in this form 10 of the invention the guard 80 has been omitted as there is no need for such guard when the invention is employed to stamp the rear end of a box.

By the use of two devices of this character 15 on a conveyor, the front and rear ends of a box traveling along such conveyor may be stamped with names, identification marks, or numbers. The distance through which the supporting means 23 is swung by the retracting means 41 is determined by the spacing of the plate 52 relative to the rear end 54 of the arm 28 so that the time at which the roller 51 makes engagement with the plate 52 may be varied.

25 The invention also includes a simple means for adjusting the printing device to proper operating position. The supporting bracket 33 has a downwardly projecting leg 100. A bolt or screw 101 secures the central portion 30 of this leg 100 to a side of the conveyor, such as the side member 12. A lateral adjustment member 102 extends from the lower extremity 103 of the leg 100 to a clamping means consisting of a bolt 104 extending 35 through a slot 105 into a leg 106 or other supporting part of the conveyor 10 positioned at a distance from the side of the conveyor on which the bracket 33 is mounted. A longitudinal adjusting means consisting of a bar 107 extends diagonally upwardly from a bolt 108 near the lower end 40 of the leg 100 to a bolt 110 which projects through a slot in the upper end of the bar 107 and is screwed into the side member 12 45 of the conveyor 10. By use of the lateral and longitudinal adjusting means 102 and 107, the bracket may be rotated forwardly or sidewardly so that the arms 28 and 43 will swing through a horizontal plane or such 50 other plane as may be necessary for proper operation of the device.

In the forms of the invention disclosed I have shown means for supporting the printing roller so that it will move through a 55 path diagonal to the path of movement of the article along the conveyor, thereby causing the roller to roll across the face of the article as it moves with the article. In addition, my preferred form of the invention includes 60 means for lifting the roller from engagement, but in some practices it may be desired to omit the means for lifting the roller from engagement, for it is characteristic of the construction shown that the arm or support 65 23 holds the printing roller in such a man-

ner that were the lifting means omitted, it would move outwardly across the face of an article and would then roll along the side of the article, finally dropping off the rear end of the article into position for engagement 70 with the front end of an approaching article. To prevent blurring of the imprint, the printing roller 16 is provided with flanges 120, as shown in Fig. 1. The peripheries of these flanges have substantially the 75 same radius as the printing elements 17, but, as indicated at 121, the peripheries of the flanges 120 are interrupted so that the printing roller is supported only by the letters or characters of the printing elements 17. In 80 the use of this construction I am able to avoid blurring of the end letters or characters of the printing elements 17 as the printing roller rolls smoothly from the peripheries of the flanges 120 to the printing elements 17. 85

Although I have herein shown and described my invention in simple and practical form, it is recognized that certain parts or elements thereof are representative 90 of other parts, elements, or mechanisms which may be employed in substantially the same manner to accomplish substantially the same results; therefore, it is to be understood that the invention is not to be limited to the 95 details disclosed herein but is to be accorded the full scope of the following claims.

I claim as my invention:

1. A stamping device adapted to print an article as it moves along a conveyor, including: a rotary printing member adapted for engagement with an end of the article; supporting means for translationally supporting said printing member to cause said printing member to move laterally as it is moved forwardly by said article; and means for lifting said printing member from engagement with said article. 100

2. A stamping device adapted to print an article as it moves along a conveyor, including: a rotary printing member adapted for engagement with an end of the article; supporting means for translationally supporting said printing member to cause said printing member to move laterally as it is moved forwardly by said article; means for lifting said printing member from engagement with said article; and means for preventing reverse rotation of said printing member as it is lifted from engagement with 115 said article.

3. A stamping device adapted to print an article as it moves along a conveyor, including: a rotary printing member adapted for engagement with an end of the article; supporting means for translationally supporting said printing member to cause said printing member to move laterally as it is moved forwardly by said article; means for lifting said printing member from engagement 120

with said article; and means for continuing the rotation of said printing member as it is lifted from engagement with said article.

4. A stamping device adapted to print an article as it moves along a conveyor, including: a rotary printing member adapted for engagement with an end of the article; supporting means for translationally supporting said printing member to cause said printing member to move laterally as it is moved forwardly by said article; and means operated by engagement with said article for lifting said printing member from engagement with said article.

15 5. A stamping device adapted to print an article as it moves along a conveyor, including: a rotary printing member adapted for engagement with an end of the article; supporting means for translationally supporting said printing member to cause said printing member to move laterally as it is moved forwardly by said article; means operated by engagement with said article for lifting said printing member from engagement with said article; and means for preventing reverse rotation of said printing member as it is lifted from engagement with said article.

6. A stamping device adapted to print an article as it moves along a conveyor, including: a supporting structure adapted to be mounted along the path of movement of the article; a rotary printing member having a printing element on the exterior thereof; means for operatively securing said printing member to said supporting structure in position for engaging said article so as to produce a rolling movement of said printing member across an end of said article; and means for determining the period of engagement of said printing member with said article, said means moving said printing member bodily from engagement with said article.

7. A stamping device adapted to print an article as it moves along a conveyor, including: a printing roller; means for movably supporting said printing roller so that said printing roller will roll across an end of said article as said article moves along said conveyor; and means for determining the period of engagement of said printing roller with said article, said means moving said printing member bodily from engagement with said article.

8. A stamping device adapted to print an article as it moves along a conveyor, including: a printing roller; means for movably supporting said printing roller so that said printing roller will roll across an end of said article as said article moves along said conveyor; and means controlled by engagement with said article for determining the period of engagement of said printing roller with said article.

9. A stamping device adapted to print an article as it moves along a conveyor, includ-

ing: a printing roller; means for movably supporting said printing roller so that said printing roller will roll across an end of said article as said article moves along said conveyor; and means operated by force received from said article for determining the period of engagement of said printing roller with said article.

10. A stamping device adapted to print an article as it moves along a conveyor, including: a printing roller; means for movably supporting said printing roller so that said printing roller will roll across an end of said article as said article moves along said conveyor; and means for moving said printing roller in an angular direction relative to said end of said article whereby to determine the period of engagement of said printing roller with said article.

11. A stamping device adapted to print an article as it moves along a conveyor, including: a printing roller; means for movably supporting said printing roller so that said printing roller will roll across an end of said article as said article moves along said conveyor; and means controlled by engagement with said article for moving said printing roller in an angular direction relative to said end of said article whereby to determine the period of engagement of said printing roller with said article.

12. A stamping device adapted to print an article as it moves along a conveyor, including: a printing roller; means for movably supporting said printing roller so that said printing roller will roll across a face of said article as said article moves along said conveyor; means for determining the period of engagement of said printing roller with said article; and means for preventing reverse rotation of said printing roller as it disengages said article.

13. A stamping device adapted to print an article as it moves along a conveyor, including: a printing roller; means for movably supporting said printing roller so that said printing roller will roll across an end of said article as said article moves along said conveyor; means for determining the period of engagement of said printing roller with said article; means for inking said printing roller; and means for continuing the forward rotation of said printing roller as it disengages said article.

14. A stamping device adapted to print an article as it moves along a conveyor, including: a printing roller; means for movably supporting said printing roller so that said printing roller will roll across a face of said article as said article moves along said conveyor; means for determining the period of engagement of said printing roller with said article; means for inking said printing roller; and means for preventing reverse rota-

tion of said printing roller as it disengages said article.

15. A stamping device adapted to print an article as it moves along a conveyor, including: a printing roller; means for movably supporting said printing roller so that said printing roller will roll across an end of said article as said article moves along said conveyor; and means for lifting said printing roller from engagement with said article.

16. A stamping device adapted to print an article as it moves along a conveyor, including: a printing roller adapted to print upon an end of said article; an arm supporting said printing roller; a pivot for said arm situated to one side of the path of movement of said article along said conveyor on which said arm may swing so as to determine a path of movement for said printing roller into and out of the path of movement of said article; and means auxiliary to said printing roller for swinging said arm.

17. A stamping device adapted to print an article as it moves along a conveyor, including: a printing roller adapted to print upon an end of said article; means for inking said roller; an arm supporting said printing roller; a pivot for said arm situated to one side of the path of movement of said article along said conveyor on which said arm may swing so as to determine a path of movement for said printing roller into and out of the path of movement of said article; and means auxiliary to said printing roller for swinging said arm.

18. A stamping device adapted to print an article as it moves along a conveyor, including: a printing roller adapted to print upon an end of said article; means for inking said roller; an arm supporting said printing roller; a pivot for said arm situated to one side of the path of movement of said article along said conveyor on which said arm may swing so as to determine a path of movement for said printing roller into and out of the path of movement of said article; and means auxiliary to said printing roller, operative in response to engagement with said article, for swinging said arm.

50 19. A stamping device adapted to print an article as it moves along a conveyor, including: a printing roller adapted to print upon an end of said article; means for inking said roller; an arm supporting said printing roller; a pivot for said arm situated to one side of the path of movement of said article along said conveyor on which said arm may swing so as to determine a path of movement for said printing roller into and out of the path of movement of said article; and means auxiliary to said printing roller, operative in response to engagement with said article, for swinging said arm, said auxiliary means having a part engaged by said article as it approaches said printing roller adapted to

swing said printing roller from the path of movement of said article whereby to prevent engagement of the front end of said article and said printing roller.

20. A stamping device adapted to print an end of an article as it moves along a conveyor, including: a cylindrical printing member; and supporting means for said printing member adapted to produce a single rolling engagement of said printing member with said end of said article.

21. A stamping device adapted to print an article as it moves along a conveyor, including: a cylindrical printing member; and supporting means for said printing member adapted to produce a single rolling engagement of said printing member with an end of said article and to cause said printing member to move through a diagonal path while it engages said article.

22. A stamping device adapted to print an article as it moves along a conveyor, including: a printing roller; means for movably supporting said printing roller so that said printing roller will roll across and imprint a face of said article as said article moves along said conveyor; and means for preventing reverse rotation of said printing roller as it disengages said article to avoid smudging of the print.

In testimony whereof, I have hereunto set my hand at Los Angeles, California, this 4th day of December, 1930.

JOHN S. PHELPS.
